US0D1013646S

(12) **United States Design Patent** (10) Patent No.: **US D1,013,646 S**
(45) Date of Patent: ** Feb. 6, 2024

(54) **CONTROLLER**

(71) Applicant: **Yuan Chen**, Hunan (CN)

(72) Inventor: **Yuan Chen**, Hunan (CN)

(**) Term: **15 Years**

(21) Appl. No.: **29/915,167**

(22) Filed: **Oct. 26, 2023**

(51) LOC (14) Cl. **14-03**

(52) U.S. Cl.

USPC **D13/168**; D24/200

(58) **Field of Classification Search**

USPC D13/162, 164, 168; D14/218; D24/128, D24/133, 200, 214, 215

Primary Examiner — Selina Sikder

(57) **CLAIM**

The ornamental design for a controller, as shown and described.

DESCRIPTION

FIG. 1 is a front perspective view of a controller showing my new design.

FIG. 2 is a rear perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof; and,

FIG. 8 is a bottom view thereof.

The broken lines illustrate portions of the controller that form no part of the claimed design.

1 Claim, 8 Drawing Sheets
